3 Claims. (Cl. 260—679)

This application is a continuation-in-part of our pending application Serial No. 164,526, filed January 5, 1962, now abandoned.

This invention relates to a process for the production of acetylene and ethylene from hydrocarbons. In particular it relates to a process of this kind in which an additional amount of hydrocarbons is added to the hot reaction mixture.

It is known that acetylene can be prepared by incomplete combustion of gaseous or vaporized hydrocarbons with oxygen by separately preheating the gases, mixing them while hot and supplying the mixture to a reaction chamber in which cracked gas containing acetylene is formed by partial combustion of the hydrocarbons. The cracked gas, after leaving the reaction chamber, is cooled by means of a coolant to temperatures below 100° C., the coolant being heated up and vaporized. The initial materials used in the prior art methods are hydrocarbons with one to ten carbon atoms in the molecule, and oxygen or gas containing oxygen, the weight ratio of hydrocarbon to oxygen being about 1:1. The gaseous initial materials are preheated to about 150° to 700° C. prior to the reaction.

A method for carrying out chemical reactions at high temperatures is also known in which hydrocarbons are added to hot, completely burnt combustion gases. This method has the disadvantage that the cracked gas is diluted by the completely burnt combustion gas so that separation of acetylene or ethylene from the said gas is rendered difficult.

In the production of acetylene and olefines from gaseous or vaporous hydrocarbons by leading them through spaces heated to high temperatures or through electric arcs and quenching the reaction mixture by injecting liquids, it is also known to add to the hot gas mixture, prior to quenching and immediately behind the zone of maximum temperature or after the production of acetylene, hydrocarbons in an amount insufficient for quenching. The amount of carbon black formed during the production of acetylene is only slightly affected by this measure.

It is an object of the present invention to provide a process for the production of acetylene and ethylene in which the ratio of acetylene to ethylene may be varied at random. Another object is the production of acetylene with reduced carbon black formation. A further object of the invention is the production of acetylene with a low consumption of hydrocarbons and oxygen.

In accordance with our invention these objects are achieved, i.e. acetylene and ethylene are produced by incomplete combustion of hydrocarbons with oxygen or an oxygen-containing gas in a reaction zone in which a maximum temperature of about 1300° to 1650° C. normally prevails and quenching the hot combustion gas with a cooling liquid by introducing an amount of hydrocarbon into the first half of the reaction zone, in addition to the reaction mixture of hydrocarbon and oxygen-containing gas during its passage through

2

the reaction zone, the said additional amount of hydrocarbon being fed into the reaction zone ahead of the point at which, had the additional feed not been made, the normal maximum temperature would occur, the said additional feed of hydrocarbons being made in such an amount that the maximum temperature of the reaction gas is reduced to 500 to 1200° C.

The term "reaction zone" as used in this specification denotes that part of the reactor which extends from the point where the flame begins and the point where the flame reaction is stopped by quenching with a coolant.

The materials used in the practice of our invention are hydrocarbons having one to ten carbon atoms and oxygen or gases containing oxygen. When these gases are reacted in the reaction chamber without an addition of other hydrocarbons being made, a maximum temperature of about 1300° to 1650° C. occurs. The reaction period is about $\frac{2}{1000}$ to $\frac{5}{1000}$ of a second. The hydrocarbons to be used as an additive to the reaction mixture are those having two to twelve carbon atoms. They are used in a liquid or vaporous form in an amount of from about 10 to 80% by weight, percentage with reference to the weight of the reaction mixture. The addition is made in the region behind the zone in which the gas mixture is ignited.

When no additional feed of hydrocarbon is made, the zone of maximum temperature is at the end of the reaction chamber slightly ahead of the point where the coolant, for example water, with which the hot gas is quenched, is injected. When an additional feed of hydrocarbon is made, the temperature does not rise to its maximum height, but rather drops to about 500° to 1200° C. in that zone of the reaction chamber where the maximum temperature would occur if the additional feed of hydrocarbon was not made.

The oxygen content of the reaction mixture is about 30% by volume ahead of the point where partial combustion begins. After ignition the oxygen content of the gas mixture decreases as the combustion advances, the additional feed of hydrocarbon being injected in the first half of the reaction zone, where the oxygen content is from 1 to 10% by volume. In the practice of our invention it is preferred to inject the additional hydrocarbon feed at the point where the oxygen content is from 2 to 5% by volume.

The advantage of the process according to this invention over similar prior art processes lies in the fact that the content of carbon black in the cracked gas is greatly decreased, so that purification of the cracked gas is simplified. The hydrocarbons to be added to the mixture of the reaction gases should preferably be used in such an amount that the reaction mixture is cooled to about 500° to 1200° C. as the yield of acetylene and ethylene is highest in this case. We have found that the composition of the cracked gas is dependent not only on the amount of hydrocarbons added to the reaction mixture but also on the distance at which the point of feed is arranged ahead of the zone of maximum temperature in the reaction chamber in which the partial combustion of the hydrocarbon takes place. If the additional feed of hydrocarbon introduced into the cracked gas in the first half of the reaction zone, the yield of ethylene is higher as compared with an addition of hydrocarbon in the second half of the reaction zone. The content of carbon black in the cracked gas falls to half the content of a cracked gas obtained by adding the hydrocarbons into the second half of the reaction zone.

The following example, given with reference to the accompanying diagrammatic drawing, will further illustrate the invention without limiting it.

3
EXAMPLE

Referring to the drawing, A is a reaction chamber in which partial combustion of hydrocarbons takes place in conventional manner. In this embodiment injection nozzles B and D are provided in the first and second half of the reaction zone for the addition of further hydrocarbon. Cracked gas leaving the reaction chamber is quenched in conventional manner by a coolant, for example, water supplied from jets C.

25 kilograms per hour of light gasoline (boiling point 30° to 100° C.) and 15.6 m.³ (S.T.P.) per hour of oxygen are heated up in separate preheaters to 320° C., mixed in a mixer, supplied to the reaction chamber A and reacted therein. The hot reaction gas is quenched with water at C at the end of the reaction chamber.

In a first and a second experiment carried out under otherwise identical conditions, 10.7 kilograms of light gasoline (boiling point 30° to 100° C.) is fed per hour through nozzle B into the first half of the reaction zone (Experiment I) and, in accordance with one of the prior art methods, into the second half of the reaction zone through nozzle D (Experiment II).

The results shown in the following table are obtained:

Table

	I	II
Acetylene content in cracked gas in percent.....	6.6	7.3
Ethylene content in cracked gas in percent.....	6.1	5.4
Content of carbon black in cracked gas g./m. ³ (S.T.P.)	2.9	6.7

From a comparison of the results in column I which corresponds to Experiment I with those in column II which corresponds to Experiment II it will be apparent that a higher percentage of ethylene and a markedly lower percentage of carbon black are obtained in Experiment I.

What we claim is:

1. In a process for the production of acetylene and 40 ALPHONSO D. SULLIVAN, *Primary Examiner.*

4

ethylene by incomplete combustion of hydrocarbons with an oxygen-containing gas and quenching the hot combustion gases with a coolant, said incomplete combustion being carried out in a reaction zone in which a maximum temperature of about 1300 C. to 1650° C. normally prevails, the improvement for substantially reducing the formation of carbon black which comprises: introducing an amount of hydrocarbon into the first half of the reaction zone in addition to the reaction mixture of hydrocarbon and oxygen-containing gas during its passage through said reaction zone, said additional amount of hydrocarbon being fed into the reaction zone ahead of the point at which, had the additional feed not been made, said normal maximum temperature would occur, the said additional feed of hydrocarbon being made in such an amount that the maximum temperature of the reaction gas is reduced to 500° to 1200° C.

2. A process as claimed in claim 1 wherein said additional feed of hydrocarbon is about 10 to 80% by weight with reference to the weight of the reaction gas at the point where it is introduced.

3. A process as claimed in claim 1 wherein hydrocarbons having 1 to 10 carbon atoms in the molecule are employed for the initial combustion and hydrocarbons having 2 to 12 carbon atoms are employed for said addition.
